UNITED STATES PATENT OFFICE.

SAMUEL TESCHER, OF DENVER, COLORADO.

UNIT FOR CRUSHING AND DISTRIBUTING POWDERED STONE IN COAL MINES.

Application filed November 20, 1924. Serial No. 751,132.

This invention relates to machines for distributing crushed rock and similar material in the form of dust to the exposed surfaces of a mine for the purpose of covering the 5 dangerous coal dust in the mine with rock dust so as to render the coal dust harmless, experimental and practical tests made by the United States Bureau of Mines having demonstrated that very fine rock dust placed 10 on the underground surfaces of coal mines is very efficacious in limiting and preventing coal mine explosions.

In common and ordinary practice the rock material is crushed very finely on the surface. It is then sacked and transported 15 into the mine for distribution and then is blown by blowers onto the rock faces and timberings of the mine. Considerable difficulty has been experienced, however, in preventing the caking of the rock dust and by 20 the waste of the "fines" in transportation, but it will be understood, of course, that the finer this rock dust is, the better and the more thoroughly it may be blown through 25 the mine and distributed upon the rock and timber faces.

The object of this invention is to reduce the expense of covering the rock faces with the rock dust as required and do this by eliminating the expense of crushing the rock 30 material on the surface, sacking it, and then transporting it into the mine for mechanical distribution, and in this connection to provide a unitary motor, crusher and fan mounted upon one bed plate and truck so that the entire unit can be transported from place to place within the coal mine workings, thus permitting the machine to be moved 35 into nearly all parts of the mine so that every crook, crevice and lodging place for the dangerous coal dust can be thoroughly covered with the rock dust so as to render the coal dust entirely harmless.

A further object is to provide a machine 40 of this character which is so designed that only the very fine material is exhausted from the crusher and blown into the mine air currents, giving a smoke screen of very fine rock dust covering the roofs, ribs and floors 45 of all the mine workings.

A still further object is to provide an equipment so designed as to shape, size and weight that it can be mounted on an ordinary mine car truck and moved from place 50 to place throughout the mine workings. In gaseous mines where it is not practicable to

move this machine with its wires into the return airways, the machine can be kept on the intake airways and pipe extensions placed from the exhaust through stoppings 60 or doors in such a manner as to reach all the workings on the return airways.

Other objects will appear in the course of the following description.

My invention is illustrated in the accompanying drawings, wherein:—

Figure 1 is a top plan view of a combined crushing and distributing unit constructed in accordance with my invention;

Figure 2 is a side elevation of the construction shown in Figure 1;

Figure 3 is an end elevation;

Figure 4 is a transverse sectional view through the stone crusher.

Referring to these drawings, 10 designates 75 a truck which has the form of a standard mine car truck and provided with the wheels 11 and the bed plate 12, the beams of the truck being connected by cross braces 13. Mounted upon this bed plate is an electric 80 motor 14 of any usual construction and having the usual shaft 15. Mounted upon the bed plate 12 is a stone crusher, designated generally 16. The casing has an opening in its top closed by a lid 17 whereby the stone 85 may be fed into the crusher. The crusher is operated by power transmitted from the motor 14 to a flexible coupling 18 which is engaged with a crusher shaft 15^a. Mounted in connection with the crusher is an exhaust 90 fan 19 carried upon the extremity of the shaft 15^a, which exhaust fan and its casing may be of any suitable construction.

The fan casing 20 is connected by a pipe 21 to the stone crusher, this pipe entering 95 at the center of the fan casing. Disposed within the fan casing is the usual exhaust fan having approximately radial blades and discharging tangentially through a tangential pipe 22. This pipe 22 may extend any 100 desired length and be formed of sections flexibly connected to each other or of flexible pipe.

A perforated screen 23 is disposed within the crusher at the lower end thereof and the 105 fan exhausting from the top of the crusher hopper draws air through this screen and hopper, picking up only the very fine materials from the crusher. The screen acts to admit air but prevents passage from the 110 crusher of such particles as would otherwise fall by gravity therefrom. At the same time,

this screen tends to divide the air passing through the crusher to prevent application thereof to the dust within the crusher at any one particular point in sufficient force to cause exhausting from the crusher of such particles as might not have been properly divided.

The crusher, as shown in Figure 4, is of a standard type and includes a rotatable element 24 mounted upon the shaft 15^a and carrying upon it the hammers 25. These hammers operate over a concave 26 having perforations through which the broken rock passes. The shaft 15^a extends through the casing 16 and into the casing 19 of the blower and the fan blades of the blower are mounted upon this shaft. One distinction between the crusher as illustrated and the crusher as ordinarily used is that the fine dust is taken out through the pipe 21 by the exhaust fan. If there was no exhaust fan the crushed rock would pass out through the perforations in the concave.

It is standard practice to connect the motor to a crushing device of this kind by means of a flexible coupling. The motor shaft extends only so far as this coupling, while the crusher shaft extends clear through the crusher sufficiently far to accommodate the centrifugal fan. As before remarked, the blower may be of any suitable character. Preferably the crusher and the fan are driven by electricity, but I do not wish to be limited to the use of an electric motor as other motors might be used.

It will be obvious that the machine is particularly mobile and can be moved into nearly all parts of the mine so that every crook, crevice and lodging place can be thoroughly covered with rock dust. Coarse rock material of shale or other non-silicious material is fed into the crusher through the hinged lid opening on the top. This material is ground up or pulverized in the crusher and the very fine powder resulting is simultaneously withdrawn from the hopper on top of the crusher through a pipe of large cross sectional area 21 into the fan and then is blown out from the fan into the air currents.

By the use of this machine, the expense of initially crushing the rock material on the surface, sacking it, and then transporting this material into the mine for mechanical distribution is avoided. Where the rock material is crushed on the surface and transported into the mine, a very large percent-

age of the very finely pulverized dust is lost, and tests have shown that this very fine material is the most efficient in actual use. By blowing this finely crushed or pulverized rock material into the mine and particularly close to the place where it is desired to cover the surface, the dust is deposited in the same manner in which the dangerous coal dust was originally deposited, that is by the travel of the air currents, thus assuring that the lodging places for the coal dust will also furnish lodging places for the rock dust.

It will be obvious, of course, that the machine will be made in sizes to suit the track gauge and clearance dimensions of any particular mine and may be varied to suit various conditions by the use of different sizes and capacities of machine, that is the track gauge can be varied, the size of the motor, the crusher, or the fan can also be varied to suit conditions which are most advantageous for any particular case. By the use of this machine within a coal mine, the rock dust has no opportunity for caking as it does where the material is crushed on the surface and then carried into the mine, but the rock dust is kept in suspension throughout the entire operation from the time it is freshly crushed until the time it is lodged on the rock faces.

In tests covering a period of ninety days, it has been demonstrated that with this machine all rock surfaces can be reached and actual dust clouds have been seen coming from the mine fans which were located at nine thousand feet from the point of operation of the machine. The depositions of dust shown by these tests have occurred on top of mine timbers, on the reverse side of mine props, in crosscuts which have been driven off of the entries in which the machine was operating, on the roofs, and on every projection and crevice in the mine surfaces throughout their entire length.

I claim:

In a stone crushing and distributing unit, a pulverizer having a feed hopper at its upper end, a grated opening at its lower end, means for introducing air under pressure through the grated opening and an outlet for finely divided material communicating with the hopper.

In testimony whereof I hereunto affix my signature.

SAMUEL TESCHER.
